UNITED STATES PATENT OFFICE.

DAVID A. CRAMER AND JOHN M. HOBEN, OF GALESBURG, ILLINOIS.

FURNACE.

1,114,969.

Specification of Letters Patent.

Patented Oct. 27, 1914.

Application filed January 15, 1912. Serial No. 671,164.

To all whom it may concern:

Be it known that we, DAVID A. CRAMER and JOHN M. HOBEN, citizens of the United States, and residents of Galesburg, in the 5 county of Knox and State of Illinois, have jointly invented a new and useful Furnace, of which the following is a specification.

Our invention relates to furnaces and particularly to that general class thereof in 10 which the grates are in the nature of traveling endless belts.

Among the main objects of the invention is to economize in the amount of fuel consumed in order to produce a given amount 15 of heat.

In grates or grate mechanisms of ordinary construction much of the time of the fireman is devoted to cleaning the grate. An object of this invention is to provide a grate 20 which is of such nature and construction that cleaning or raking will be practically unnecessary.

To provide a furnace in which practically all the gas and smoke will be consumed— 25 thereby aiding in consummating the first recited object—is an object.

To provide a novel grate *per se*, which is especially adapted for the general purpose of the invention, is an object.

30 To provide simple and efficient means whereby the grate may be operated at will is a further object.

It is an object to provide novel means at the rear end of the grate which performs the 35 twofold function of preventing a counter current of air entering into the combustion chamber or fire-box and interfering with either the fire or the draft and of aiding in dislodging from the grate bars any ashes or 40 cinders which may have become attached thereto.

The grates of automatic stokers necessitate a particular kind of fuel for successful operation.

45 It is an object of our invention to provide a traveling grate which will produce perfect results with any kind of solid fuel.

Therefore, the principal end and object is to generally improve the construction and 50 increase the capacity, utility and efficiency of this character of devices.

Minor objects will be in part obvious and in part pointed out.

To the attainment of the foregoing ends 55 and objects the invention consists in the novel construction, certain novel combina-

tions, and the adaptation of certain parts hereinafter described and claimed.

In the accompanying drawings, which illustrate a preferred embodiment of our invention: Figure 1 is a top plan, partly broken away; Fig. 2, an enlarged detail of the link, a side elevation, seen from the inside; Fig. 3, an enlarged detail, a bottom plan, partly in section, of the link; Fig. 4, a 60 side elevation, partly in longitudinal section; Fig. 5, a front elevation, partly in section; Fig. 6, a perspective of one of the grate-sections; and Fig. 7, an enlarged end view thereof.

Throughout the several views like parts are identified by like reference characters.

2, 2 designate longitudinally arranged inverted L-shaped or angle iron base-bars, the vertical portions of which are provided at 75 their forward ends with apertures for the reception of a shaft 3 carrying fixed sprocket-wheels 4 and a cog-wheel 5 by which said shaft and wheels are actuated. Near the rear ends of the vertical portions 80 of the bars 2 are apertures in which are seated a shaft or rod 14 carrying idlers 6.

6' designates a transverse base-bar.

7 indicates the front wall, provided with fuel openings 8, one only of which is shown. 85

9, 9 are frame-plates, each provided with a notch 10, in which notches rest the ends of transverse rail-supporting bars 11. Rails 12, suitably seated and held from displacement by cutaway portions providing shoulders, as 90 indicated at 13, or held in any other suitable manner, rest upon the bars 11 and provide a support over which the upper flight of the endless grate hereinafter described may travel.

95 The bars 11 may be removed by lifting them from the notches 10, and the rails 12 by lifting them from the restraining shoulders 13.

An actuating shaft 15 is mounted in ears 100 16 fixed to the front wall 7, and at one end carries a fixed cog-wheel 17 meshing with the wheel 5. A ratchet wheel 19 is fixed midlength of the shaft 15 and is adapted for intermittent actuations by a dog 20 pivoted 105 to any suitable ratchet lever 21.

Each grate-section 22 shown comprises spaced longitudinal bars 23, transverse intermediate bars 24 providing an arch 25, transverse projections 26, and longitudinally 110 disposed studs 27 provided each with a boss 29. The several grate-sections are connected

by links 30, each provided at its inner portion with recesses 31 which extend slightly beyond its longitudinal central line and which communicate with transversely arranged apertures 32 extending through the link. Oblong apertures 33 are provided in the bottom of the link and communicate with the recesses 31 and apertures 32. To assemble the sections 22 one of the studs 27 and 10 bosses 29 is slipped into a recess 32 and the boss turned to rest in the aperture 33, the lower wall of which aperture will restrain it (the link) from outward movement with relation to the boss 29. The outer end of 15 the stud 27 will rest in the aperture 32. The proximal stud and boss of an adjacent section 22 is then likewise connected with the link and like processes proceeded with until the complete endless grate is assembled.

20 Shown best at Fig. 4 is a preferred embodiment of that part of our invention which relates to the means for preventing counter currents of air from entering either the ash pit or fire-box and in any manner interfering with the draft or the combustion, and which further automatically acts to scrape off any adhering cinders which may have adhered to or been caught in or between the grate-bars or sections. A keeper 25 34 is suitably fixed, as by screw-bolts 35, to each bar 2. A rod 36 is seated in the eyes of each keeper. One section, 37, of a gravity-actuated swinging hood is provided with lugs 39, the eyes of which loosely receive the rod 36. The forward section, 40, of the hood extends in close proximity to that portion of the belt-like grate which is embracing the idlers, and the lower section, 41, is arcuate and concentric to said rod, 30 whereby its lowermost portion will be at all times almost in contact with the surface above which it swings, thus preventing drafts of air from entering from behind. The sections above designated by numerals, 45 45 as also a connecting section 42, are preferably lap-jointed and riveted as shown, for convenience in manufacture.

We now proceed to a description of the operation: A fire being on the grate, if a sufficient amount of air is not being furnished, the operator will impart intermittent reciprocations to the lever 21 to impart movement to the ratchet-wheel 19, shaft 15, geared wheels 17, 5, shaft 3 and sprocket-wheel 4. 50 The teeth of the latter will contact the bars 23 and drive forward to the predetermined position the upper flight of the assembled grate. The rear portion of the fire will by this operation have been dumped into the 55 ash-pit—the clinging or adhering cinders, if any, having been scraped off by the forward edge of the hood section 40. The operator will then draw forwardly a small amount of the live coals and thereon add fresh fuel. 60 65 The smoke of the newly built fire will, be-

cause of the draft, have a tendency to pass to and over the live fire at the (then) rear portion of the grate, and will be consumed thereby, thus effecting not only economy of fuel but obviating also the objectionable 70 smoke discharge. It will be evident that while the rear fire is exhausting itself the forward one is growing into life, and that by the time the first is practically dead, the other has reached a state of perfect combustion, whereby an approximately equal degree of heat may at all times be maintained in the fire-box. The rear fire constitutes what corresponds to the bridge wall of an ordinary furnace and none is required 75 when our improvements are used.

It is necessary to "drag" or "rake" ordinary furnaces through the feed doors. The operation requires a considerable length of time, and the consequence is that cold air 80 inrushing through the open door, over the live coals, will check the fire and cool the exposed boiler surface.

Dumped coals, with our construction, will not lie in contact with, to heat and burn out 85 the lower flight of the grate, for the forward motion thereof will drag said coals free from contact therewith.

It has been thought neither necessary nor best to encumber this specification and the 90 accompanying drawings with descriptions and illustrations of modifications or of elements or parts which are neither essential to nor form any part of the invention herein claimed. In fact, it is apparent without 95 such, that numerous changes may be made in the details of construction and by modifications involving only mechanical skill, without departing from the spirit, scope, and 100 general idea of the invention.

Therefore, without limiting ourselves to particularities or to the precise construction shown, we claim as new and desire to secure by Letters Patent the following, to wit:

1. A furnace comprising longitudinally arranged L-shaped base-bars, an idler shaft seated in bearings in the vertical webs thereof, idlers on said shaft, a driving shaft seated in other bearings in said vertical webs, sprocket wheels fixed thereon, oscillatory means for imparting rotatory movements to said driving shaft, an endless grate embracing said idlers and sprocket wheels and actuated by the latter, removable track-rails supporting the upper flight of the grate, removable transverse bars supporting said rails, plates secured to the base-bars and removably supporting said transverse bars, and a swinging hood pivoted to the rear portions 115 of said base-bars and in rear of said grate, its upper end being in close relation thereto.

2. A traveling grate comprising grate sections, each section comprising spaced longitudinally arranged bars, transversely ar- 120 125 130

ranged bars intermediate said bars, and providing an arch and each section having studs provided each with a boss, and a link connecting the adjacent ends of each pair of sections, each of said links provided at its inner portion with recesses which extend beyond its longitudinal central line and which communicate with apertures extending through the link, each link provided also **10** with an aperture which communicates with a recess and an aperture above recited, each of said studs adapted to enter one of the first recited apertures and each of said bosses

adapted to enter one of said recesses and to be turned into one of the second recited apertures to lock the link on the grate section. **15**

In witness whereof we hereunto affix our signatures at Galesburg, in the county and State above written, this 29th day of December, 1911.

DAVID A. CRAMER.
JOHN M. HOBEN.
